UNITED STATES PATENT OFFICE.

HAZEN RITCHIE, OF PETERBORO, CANADA.

PLAYING-BALL.

No. 818,050.

Specification of Letters Patent.

Patented April 17, 1906.

Application filed March 11, 1905. Serial No. 249,625.

To all whom it may concern:

Be it known that I, HAZEN RITCHIE, a subject of the King of Great Britain, residing at Peterboro, in the county of Peterboro, Province of Ontario, in the Dominion of Canada, have invented new and useful Improvements in Playing-Balls, of which the following is a specification.

This invention relates to improvements in playing-balls as described in the present specification and illustrated by the accompanying drawings, that form a part of the same.

The invention consists, essentially, of a ball comprising a hollow metal core spherically formed of a plurality of segments having finished edges and secured together at their convergent points and a gum-material covering.

The objects of the invention are to simplify the construction of this particular class of article by minimizing the number of operations necessary in the manufacture thereof and to attain high efficiency in the rebounding qualities. This last feature will be particularly appreciated by the player in the game of golf, relieving as it does to a large extent the physical exertion necessary in making a long drive, and thus insuring a greater accuracy of direction after the ball leaves the club.

Referring to the drawings, Figure 1 is a perspective view of the metal core as it appears secured together at their convergent points. Fig. 2 is a perspective view of one of the segments forming the spherical metal core. Fig. 3 is a perspective view of a second segment of the spherical metal core. Fig. 4 is a perspective view of a third segment of the core. Fig. 5 is a perspective view of a fourth segment of the core. Fig. 6 is a sectional view of the playing-ball, showing the position of the coverings in relation to the metal core. Fig. 7 is an enlarged perspective view of a segment broken away to show the finished edges. Fig. 8 is a perspective view of the metal core having longitudinal slits in the segments.

Like letters of reference indicate corresponding parts in each figure.

a is the metal core, formed of the segments *b*, *c*, *d*, and *e*. The segments *b*, *c*, *d*, and *e* are preferably made from thin sheets of steel

and tempered and having turned edges *k*. The segments are secured together at their convergent points *f* and *g* in any suitable manner, but securely, so that they will hold firmly together no matter what the impact may be nor how wide the breaches between the segments may open.

h is the inner covering of the core and is made preferably of a gum material, such as gutta-percha, and suitably compressed over the core.

i is an outer covering of a similar nature as the inner covering *h*, though of somewhat different consistency, as usual in golf-balls. The covering *i* is compressed over the inner covering *h* in any approved form in the manufacturing of the ball.

The advantages of this invention are very material, particularly referring to the simple method of construction.

It will be noticed in the foregoing description that the segments are made from thin sheets of steel, capable of taking a spring-temper. This will enable in the manufacture of the core the stamping out of the segments in one operation in readiness to be tempered.

The securing of the segments together is easily accomplished, and with the modern means of soldering metals there is no reason to fear that the segments will part at their convergent points through hard usage.

In the use of the ball the high efficiency as regards speed is attained by the formation of the core from segments separated and in the shape of a hollow sphere.

It will be readily seen that on impact the core will give and quickly rebound to its original position, for as the ball receives the blow the breaches are widened between the segments intermediate of the soldering-points, and immediately after the impact the spring-temper segments resume their normal position.

In Fig. 8 I have shown a core having slits *j* made in the segments, here shown longitudinally. The slits *j* may be merely cuts in the segments or may be more in the form of slots, if desired, the main object being to secure greater flexibility in the core if found necessary in some constructions.

It may be found an advantage in securing the segments together to leave a very slight

breach therebetween, but not sufficient to affect the general appearance of the core as a complete sphere; otherwise the durability would not be a salient feature of the invention, as it undoubtedly is.

What I claim as my invention is—

1. A playing-ball, comprising a hollow spring-metal core formed of a plurality of segments suitably secured together at their convergent points, and longitudinally separated therebetween, and a gum-material covering, as and for the purpose specified.

2. A playing-ball, comprising a hollow metal core formed of a plurality of distinct and separate segments, having slots therein, means for securing said segments together at their convergent points only, and a suit-

able covering, as and for the purpose specified.

3. A playing-ball, comprising a hollow metal core formed of a plurality of distinct and separate segments, having longitudinal slots in the bellying portions thereof, means for securing said segments together at their convergent points only, and a suitable covering, as and for the purpose specified.

Signed at Peterboro, in the Province of Ontario, in the Dominion of Canada, this 7th day of March, 1905.

HAZEN RITCHIE.
